G. FRIEDRICH

COLLAPSIBLE UMBRELLA

Filed May 27, 1925

FIG. 1

FIG. 2

FIG. 4

INVENTOR
G. Friederichs
BY
J. Pedermann
ATTORNEY

UNITED STATES PATENT OFFICE.

GUSTAV FRIEDRICH, OF MADISON, NEW JERSEY.

COLLAPSIBLE UMBRELLA.

Application filed May 27, 1925. Serial No. 33,088.

The main object of this invention is to provide an umbrella frame which may be entirely collapsed so that the same may be conveniently folded and stored in an ordinary 5 pocket.

The above and other objects will become apparent in the description below, in which characters of reference refer to like-named parts in the drawing.

10 Referring briefly to the drawing, Figure 1 is a front elevational view of the frame in elongated position in which it is ordinarily used.

Figure 2 is a sectional elevational view of 15 the handle, showing the same in collapsed position.

Figure 3 is a fragmentary view of a section of the rib, showing the means of supporting the outer or end rib member by the 20 arrangement provided.

Figure 4 is a view similar to Figure 3, showing the rib sections in folded position.

Referring in detail to the drawing, the 25 numeral 10 indicates a solid stud circular in cross section and upon which a pair of rings 11 and 12 are adapted to be slipped, the ring 11 being secured rigid after being slipped into place on the stud 10. The stud 10 is slidably mounted in a length of tubing 13 which 30 is provided with a flanged upper end 14 engaged by a lug 15 formed at the lower end of the stud 10. An additional tubular section 16 is adapted to receive the section 13 and is in turn adapted to telescope into a 35 lower tubular section 17 which is flared outwardly at its lower end to provide a handle grip 18. A slot 19 is formed in the tubular section 16 and extends thru the greater portion of the length of said sleeve having an 40 off-set slot 20 at its lower end, said slot communicating with the longitudinal slot 19. A pin 21 anchored to and projecting from the side of the tube 13 is movable in the slot 19 and when entered into the slot 20, is adapt- 45 ed to fix member 13 within member 16. A similar longitudinal slot 22 is formed with the lower tube 17 and at its lower end also has an off-set slot 23 in either of which a pin 24 fixed to the lower end of the tube 16 is 50 slidable. A relatively long coil spring 25 is mounted within the tubular sections between the bottom 26 of the lowest tubular section and the bottom of the stud 10, as illustrated in Figure 2. A plurality of ribs 27 are piv- 55 otally joined to the upper ring 11 and radiate outwardly therefrom. Each of these

rib sections terminate in a downwardly extending boss or ear 28 in which a pin 29 is anchored. To these pins, the support ribs 30 are pivoted, the opposite ends of said support ribs being pivotally anchored to the lower ring 12 which is centered on the stud 10. These support ribs are each provided with a slot 31 thru which a semi-circular supporting ring 32 passes. One end of said supporting ring is pivotally attached to the rib section 27 and extends downwardly semi-circularly having its opposite end pivotally secured at the corner of a boss 33 formed on the end ribs 34, said end ribs being pivotally joined to the outer ends of the rib sections 27 by plates 35.

In collapsing the umbrella frame, the two rings 11 and 12 are slipped from the stud 10 upon which they are normally mounted 75 when the umbrella is in use. The supporting ribs 30 are then urged upwardly to align with the ring to come as close as possible to the ring 11. In doing this, the supporting ribs 30 fall into position parallel with the 80 rings 27, which position is arrived at when the rib sections 27 suspended vertically downward from the ring member 11. After this has been accomplished, the end rib members 34 are rotated upwardly so that these 85 end ribs lie in a position indicated in Figure 4, in which they extend parallel to the rib sections 27. The handle illustrated in Figure 2, being a separate member, may be telescoped by sliding section 16 into section 90 17, and section 13 into section 16, and the stud 10 into the tubular section 13. As member 16 is completely telescoped into the tubular section 17, both ends of the handle are twisted in opposite directions so that the 95 pin 24 anchored to the tubular section 16 enters into the slot 23 and fixes member 16 within the lower tubular section 17. The tube 13, forming an intermediate part of the handle, is locked in telescoped position with 100 the tube 16 in the same manner by rotating member 13 when the same has been completely collapsed into the tube 16 so that said pin 21 enters into the off-set slot 20. In the manner described, it will be seen that an 105 umbrella frame is presented which is completely collapsible into two sections, the shed frame which may be folded into a compact bundle half the length of a rib, and a handle which may be telescoped to one quarter of 110 the length. The fabric ordinarily used to cover the rib sections is herein omitted for

the sake of clarity, but it is to be noted that an expanse of material is to be used over the rib sections 27 and 34 as a protective covering.

5 I claim:—

An umbrella frame comprising a pair of rings, a handle bar supporting said rings, ribs extending radially from said rings, said ribs comprising two members, a rib member 10 attached to the ring and an end rib member pivotally attached to the outer end of said rib supporting ribs for supporting the outer ends of the first-named rib sections, the two members forming a rib being placed end

to end and pivotally connected, a semi-circular ring pivotally connected to the mutually adjacent ends of the rib sections, the supporting ribs having slots therein serving as a passage for the semi-circular rings, the end of said slot being adapted to form a stop 15 for the ring members when the latter are supporting the end rib sections in used position said ring member serving as a brace for supporting the end rib section in angular extended position.

20 In testimony whereof I affix my signature.

25 GUSTAV FRIEDRICHs.
